DESIGN FOR A COSTUMER

Onnie Mankki, Cleveland Heights, Ohio, assignor
to Designers for Industry, Inc., Cleveland, Ohio, a corporation of Ohio

Application April 16, 1945, Serial No. 119,029

Term of patent 7 years

(Cl. D33—8)

To all whom it may concern:

Be it known that I, Onnie Mankki, a citizen of the United States, residing at Cleveland Heights, in the county of Cuyahoga and State of Ohio, have invented a new, original, and ornamental Design for Costumer, of which the following is a specification, reference being had to the accompanying drawing, forming a part thereof, in which:

The single view is a perspective view of a costumer embodying my new design.

I claim:

The ornamental design for a costumer, substantially as shown.

ONNIE MANKKI.
